UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,275,527.

Specification of Letters Patent. Patented Aug. 13, 1918.

Application filed July 3, 1914. Serial No. 848,743.

To all whom it may concern:

Be it known that I, JAMES R. CARDWELL, a citizen of the United States, and resident of Chicago, county of Cook, and State of Illinois, have invented certain new and useful Improvements in Draft-Gears, of which the following is a specification and which are illustrated in the accompanying drawings, forming a part thereof.

10 The invention relates to draft gears for railway cars and particularly to that type of device which forms the subject of Letters Patent No. 819,266, granted to me May 1st, 1906.

15 In the draft gear of said Letters Patent the yielding resistance to stresses communicated through the coupler is obtained largely through the frictional engagement of various movable elements, held in normal relation and supplemented in their action by springs. The springs are carried by a transverse rod passing through a plurality of friction elements of the gear. Two of these elements constitute abutments for the 20 springs, which are mounted upon the end portions of the rods, such elements having both longitudinal and lateral movement. An intermediate frictional element, also sleeved upon the rod has longitudinal movement only.

25 In practice it frequently occurs that the friction between this intermediate element and the frictional elements with which it cooperates at the farther end of the gear, with reference to the direction of application of stresses, is sufficient to prevent its movement during the earlier stages of the compressive action. While this delayed movement of the intermediate member is not of 30 itself objectionable, but, on the contrary, results in a smoother action and more gradual development of the frictional resistance, it places upon the rod undesirable bending strains. As the rod is necessarily carried 35 with the two outer frictional elements which are mounted upon it during this stage of the action, there is a tendency to bend the rod, held as it is, midway of its ends by the intermediate element, while being strained 40 laterally by the outer elements.

The object of the present invention is to overcome this tendency to bend the rod, while permitting independent longitudinal movement of the frictional elements mounted upon it. This object is attained by, and

the invention consists in, providing one or more of such frictional elements, and preferably the center one, with an elongated aperture for the reception of the rod.

In the accompanying drawings illustrating the invention,—

Figure 1 is a detail plan view of the framing of a car and of the draft gear, being partly in section; and

Fig. 2 is a sectional view on the line 2—2 of Fig. 1.

There is shown at 10—10 a pair of center sills and at 11 an end sill. The coupler is shown at 12 and its rear extension or yoke at 13. A pair of keys or bars 14, 15, extend through elongated slots of the center sills, and through the yoke 13 and constitute the followers for transmitting stresses from the draft gear to the sills. The gear proper comprises a pair of box shaped members, 16, 17, one associated with and slotted to fit upon each of the follower bars 14, 15; two pairs of triangular wedge blocks 18, 19 and 20, 21, each pair being seated within one of the box shaped members and against a vertical transverse wall thereof; a central wedging element 22 having its ends beveled to fit between and frictionally engage the members of the two pairs of triangular wedge blocks; two outer wedging elements 23, 24, each having the inner faces of its end portions beveled to engage the outer faces of the triangular wedge blocks; a bar 25 extending through the center wedging element and the two outer wedging elements and through the center sills, which are slotted to permit its lateral movement; and springs 26, 27, coiled about the rod and located outside of the car sills, these springs reacting between the two outer wedging elements 23, 24, and abutments 28, 29, mounted upon the outer ends of the rod.

As the coupler 12 is moved longitudinally in either direction, one of the follower bars 14, 15 travels with it, advancing the box like elements 16, 17, against which it bears and with it one pair of the triangular wedging blocks, which, as they advance, move the outer wedging elements 23, 24, outwardly against the resistance of the springs 26, 27, also carrying them forwardly, sliding them upon the triangular wedging blocks at the opposite ends of the gear. The rod 25 is necessarily carried laterally by the longitudinal movement of the wedging elements 23,

24. The intermediate wedging element 22 is also urged longitudinally by the advance of a moving pair of triangular blocks and tends to spread apart the triangular blocks 5 at the other end of the gear. This advance of the intermediate frictional member is resisted by the friction between it and the triangular blocks which it tends to spread apart and also by the frictional engagement 10 of these blocks with the transverse wall of the member 16 or 17 against which they are seated.

In order to prevent the application to the 15 rod 25 of bending strains by reason of the unequal longitudinal movement of the member 23, 24, and of the member 22, I elongate the aperture 30 in the latter member so that the rod may move laterally in either direction from its central position before being 20 checked in this movement by the member 22 should the latter remain stationary, and thereby relieving the rod of any bending strains due to the application of lateral stress upon its ends with resistance intermediate of the points of such application.

As heretofore constructed and as shown 25 in my earlier patent, the rod was called upon to assist in the longitudinal movement of the central wedging element 22. In practice 30 it has been found that the rod is unequal to

the performance of this function in many instances and consequently becomes bent, a serious disadvantage to the operation of the mechanism.

I claim as my invention,—

1. A draft gear comprising central and outer frictional elements, a rod extending through such elements, and springs mounted upon the rod and bearing against the outer frictional elements, the central and the outer 40 frictional elements being longitudinally movable and being capable of relative longitudinal movement, one of said sets of friction elements holding the rod against lateral movement independently of said ele- 45 ments.

2. A draft gear comprising central and outer frictional elements both capable of longitudinal movement, a rod extending through such elements, and springs mounted 50 upon the rod and bearing against the outer frictional elements, the central frictional elements having an elongated aperture for the reception of the rod, such rod fitting snugly in the apertures in the outer frictional ele- 55 ments.

JAMES R. CARDWELL.
